(57) **CLAIM**

The ornamental design for a folding shade of washi fabric, as shown and described.

DESCRIPTION

FIG. 1 is an isometric of a front view of the folding shade of washi fabric of this design in a fully closed condition;

FIG. 2 is an isometric of a rear view of the shade in a fully closed condition;

FIG. 3 is an isometric of a front view of the shade in a partially closed condition;

FIG. 4 is an isometric of a rear view of the shade in a partially closed condition;

FIG. 5 is a side elevation of the shade in a fully open condition;

FIG. 6 is an isometric of a front view of the shade in a fully open condition; and,

FIG. 7 is a side elevation of the shade in a fully open condition.
